UNITED STATES PATENT OFFICE.

CARL HEINRICH, OF SOMERVILLE, MASSACHUSETTS, ASSIGNOR TO BERTRAND L. MAKEPEACE, INC., A CORPORATION OF MASSACHUSETTS.

LOCKING DEVICE FOR SURVEYING INSTRUMENTS AND THE LIKE.

1,341,210.

Specification of Letters Patent.

Patented May 25, 1920.

Application filed June 30, 1919. Serial No. 307,849.

To all whom it may concern:

Be it known that I, CARL HEINRICH, a subject of the Government of Hungary, and a resident of Somerville, in the county of 5 Middlesex and Commonwealth of Massachusetts, have invented certain new and useful Improvements in Locking Devices for Surveying Instruments and the like, of which the following is a specification.

10 This invention relates to locking devices designed primarily for use in connection with surveying instruments wherein the telescope is required to be firmly held in place and yet readily removable therefrom.

15 Various devices have been used heretofore among which was a pin which was attached to one portion of the Y of an instrument by a cord and adapted to enter registering holes of the two parts of the 20 Y to thereby hold them in locked position. This has been a very unsatisfactory method as it commonly happened that the cord would become worn or broken and the pin would be lost.

25 Another device consisted of a movable slide mounted on the stationary part of the Y having an overhanging lip adapted to pass over a projection on the movable portion of the Y. This method also is faulty 30 as care had to be used in handling the instrument so that accidental displacement of the aforementioned slide would be avoided.

An object of the present invention is to 35 produce a neat, readily operated locking device that is at all times securely attached to the Y, and constitutes a positive lock that will not shake loose.

Another object of the invention is to produce a simple and slight device with a 40 minimum number of parts that is perfectly satisfactory in performing its function.

Another object of the invention is to produce a device that may be rapidly locked 45 or unlocked without any especial attention of the user other than a slight twist of the locking screw in one direction or the other or until the screw comes to a stop.

The primary object of the invention is 50 to produce a locking device of extreme simplicity, neat in appearance, cheap to manufacture and positive in its action.

The invention consists in certain novel 55 features of construction and arrangement of parts which will be fully understood by

reference to the description of the drawings and to the claims hereinafter given.

Of the drawings:

Figure 1 represents an elevation of a Y, embodying the present invention, and shown 60 as in locked position with an indication of a telescope in place.

Fig. 2 represents a left view of Fig. 1.

Fig. 3 represents a partial section on the line 3, 3 on Fig. 2.

Fig. 4 represents a detail of a portion of the movable part of the Y showing the receptacle for the locking screw which is indicated by dotted lines just before and after entering the receptacle.

Fig. 5 represents a detail of the locking screw as it would appear when removed from Fig. 1.

Fig. 6 represents a right view of Fig. 5.

Similar characters designate like parts 75 throughout the several figures of the drawings.

Referring to the drawings, 10 is a Y, a fixture well known among users of surveying instruments and used chiefly in retaining the telescope in its proper place with relation to the rest of the instrument. As is well known, it is sometimes necessary to remove the telescope from its accustomed position in order to make adjustments, repairs, etc., and for this purpose devices have been designed to permit of the ready removal of the telescope without the services of a skilled workman or the use of 80 tools.

In this instance, and as usual, the Y is made in two parts, a stationary part 11 and a movable part 12 the two parts being hinged at 13 and diametrically opposite the hinge at a convenient point the locking 95 screw 14 is provided.

The part 11 has a boss 15 which is drilled and tapped at 16 to receive the threaded shank of the screw 14.

A lug 17 extends outwardly from the boss 100 15 and acts as a stop device for the screw 14 as will be hereinafter explained.

The movable part 12 of the Y 10 is likewise drilled and tapped as at 18 and a portion of the metal is removed as at 19 105 to form an entrance for the flattened portion 20 of the screw 14.

For convenience of manipulation and to prevent the accidental withdrawal of the screw 14 and to also act as one member of 110

a stop device, the screw 14 is provided with the pin 21.

Figs. 1 to 3 inclusive show the device in locked position and for simplicity of drawing an indication only of a telescope 22 is made.

If it is desired to remove the telescope from the Y, the pin 21 will be turned in the direction of the arrow *a* of Fig. 2 until the left portion of the said pin contacts with the lug 17 when the partial rotation of the screw 14 will be stopped.

This partial rotation of the screw has changed the position of its flattened portion 20 so that it now lines up with the entrance 19 previously referred to.

By grasping the finger piece 23 of the movable part 12, said part may now be raised as indicated by dotted lines Fig. 1, 20 sufficiently to allow of the removal of the telescope 22.

On the other hand, to replace the telescope 22 it is again set in its position in the Y 10 and the part 12 lowered into position 25 Fig. 1, at which time the flattened portion 20 of the screw 14 will have passed through the entrance 19 of the part 12 and into the threaded receptacle 18 and a partial turn of the screw 14 opposite to the direction of the arrow *a* will be made until the right portion of the pin 21 meets the lug 17.

Preferably both parts 11-12 of the Y 10 are threaded to receive the screw 14 as it effectually ties the two parts 11-12 with the screw 14 and obviates any tendency toward looseness of the parts.

In order to assemble the screw 14 with the part 11, the screw is first turned into the boss 15 the required distance with its flattened portion 20 in register with the entrance 19 at which time the hole to receive the pin 21 will be in a vertical position and the pin 21 is then driven in.

The pin 21 acts as a handy device to turn the screw 14, and further acts as a positioning device for the flattened portion 20 in conjunction with the lug 17 and also effectually prevents the accidental withdrawal of the screw from its place.

While this invention has been shown and described in connection with surveying instruments it is obvious that it is equally valuable in other arts and it is not the intention to limit the claims to this particular construction as slight changes may be made without departing from the spirit and scope of the invention.

Having thus described my invention, I claim:

60 1. In a locking device of the class described, a standing part, a movable part, a locking means attached to said standing part comprising a circularly movable threaded member capable of advancing and retracting in the direction of its axis a par-

tial rotation of which enables it to positively engage both of said parts, and means to limit the rotation of said locking means for the locking and unlocking movements thereof.

70 2. In a locking device of the class described, a standing part, a movable part, a locking means movable about its own axis permanently attached to said standing part capable of advancing and retracting in the 75 direction of its axis during the operations of locking and unlocking, and means to limit the movement of said locking means.

3. In a locking device of the class described, a standing part, a movable part, a 80 locking means permanently attached to one of said parts, means to rotate said locking means, means to limit the rotation of said locking means, and a coacting receptacle for said locking means capable of close ad- 85herence to said locking means.

4. In a locking device of the class described, a standing part, a movable part hinged to said standing part, a rotatable locking means capable of advancing and 90 retracting in the direction of its axis adapted to rotate about its axis to positively engage both of said parts and capable of disengagement from one of said parts, and means on one of said parts to enable it to 95 assume engaging position with said locking means.

5. In a locking device of the class described, a standing part, a movable part, a locking means constantly in engagement 100 with one of said parts and protruding into the path of the other of said parts, means such as a receptacle in said movable part to permit the engagement of said locking means with said movable part, means 105 such as finger pieces to facilitate in the rotation of said locking means to engage said last mentioned part and a stop device to limit the rotation of said locking means.

6. In a locking device of the class de- 110 scribed, a standing part, a movable part, a screw permanently attached to said standing part and protruding into the path of the movable part, threads in both of said parts adapted to be engaged by said screw 115 when said parts are in locked position and disengaged from the threads of the movable part when the parts are in unlocked position, means on the movable part to permit it to assume engaging position with said screw, 120 and means to rotate said screw whereby it will engage the threads of said movable part.

7. In a locking device of the class described, a standing part, a movable part, a screw permanently attached to said stand- 125 ing part, said screw having a flattened portion at the end thereof protruding into the path of the movable part, a receptacle for said flattened portion, means to permit said flattened portion to enter said receptacle, 130

and means to rotate said screw whereby the threads of said flattened portion will engage the threads of the said movable part.

8. In a device of the class described, a standing part, a movable part, a screw permanently attached to said standing part having a flattened portion protruding into the path of said movable part and adapted to be engaged with or disengaged from said movable part, a threaded receptacle for said flattened portion, a slot in said movable part leading into said threaded receptacle, means to rotate said flattened portion in said receptacle, and means to limit the rotation of said flattened portion.

9. In a device of the class described, a standing part, a movable part hinged thereto; a threaded boss on said standing part adapted to receive a screw; a screw in said boss having projections extending therefrom; a threaded receptacle in said movable

part having a lateral entrance thereto adapted to receive the end of said screw; and a stop device on said standing part adapted to coact with said projections to limit the rotation of said screw.

10. In a device of the class described, two members movable relatively toward and from each other the free ends of which overlap and adapted to abut each other; a threaded hole in one of said members; a threaded receptacle registering with said threaded holes having a lateral entrance thereto in the other of said members; a locking member in said threaded hole; means to rotate said locking member; and means to limit the rotation of said locking member.

Signed by me at 4 Post Office Square, Boston, Mass., this 21st day of June, 1919.

CARL HEINRICH.
